(57) **CLAIM**

The ornamental design for a set of window reveals, as shown and described.

DESCRIPTION

FIG. 1 is a perspective view of the set of window reveals showing our new design;

FIG. 2 is a front view of the set of window reveals of FIG. 1;

FIG. 3 is a left view of the set of window reveals of FIG. 1; FIG. 4 is a right view of the set of window reveals of FIG. 1;

FIG. 5 is a top view of the set of window reveals of FIG. 1; and,

FIG. 6 is a close-up perspective view of one window reveal of the set of window reveals of FIG. 1.

The evenly spaced broken lines in FIGS. 1-6 depict environmental structure that form no part of the claimed design. The dash-dot-dot lines surrounding the detail views in FIGS. 1 and 6 are for the purpose of annotating the detail views only and form no part thereof. The dash-dot-dot-dot lines in FIGS. 1, 2, 5, and 6 illustrate boundaries of the claimed portions of the design and form no part thereof. The set of window reveals is shown with a symbolic break in its length. The appearance of any portion of the article after the break lines, as well as the break lines themselves, form no part of the claimed design.
